UNITED STATES PATENT OFFICE.

FRANCIS I. DU PONT, OF WILMINGTON, DELAWARE, ASSIGNOR TO DELAWARE CHEMICAL ENGINEERING COMPANY, OF WILMINGTON, DELAWARE, A CORPORATION OF DELAWARE.

MEANS FOR PREVENTING THE FORMATION OF SCALE IN STEAM-BOILERS.

1,401,893.

Specification of Letters Patent. Patented Dec. 27, 1921.

Application filed May 31, 1918. Serial No. 237,450.

To all whom it may concern:

Be it known that I, FRANCIS I. DU PONT, a citizen of the United States, residing at Wilmington, county of New Castle, and 5 State of Delaware, have invented a new and useful Improvement in Means for Preventing the Formation of Scale in Steam-Boilers, of which the following is a full, clear, and exact description, reference being had to 10 the accompanying drawings, which form a part of this specification.

The object of my invention is to automatically maintain a constant level of water in a steam boiler and deliver feed water there- 15 to in a highly heated condition and at the same time maintain the boiler constantly replenished with sufficient fresh water to prevent the formation of scale or reduce the formation of scale to a minimum.

20 In an application filed by me March 29, 1918, I have set forth an apparatus accomplishing the first two of the above specified objects and exhibiting other features of novelty and importance. The present invention 25 embodies the invention of said application, but is a specific modification thereof.

The preferred construction in which the invention of said application is embodied comprises means to pump water from a 30 water reservoir or tank to the boiler, means to return water from the boiler to the tank at a rate exceeding, or at least not less than, the rate at which the water is pumped to the boiler, a heat interchanger arranged to trans- 35 fer heat from the water flowing away from the boiler to the water flowing toward the boiler to prevent the waste of heat that would otherwise occur, and means to prevent the conversion into steam of the water flowing 40 from the boiler so as to insure the exchange of the maximum amount of heat before the return of the water to the tank.

The present invention embodies preferentially the same features of construction except that the feed pump, instead of pumping water from the reservoir into which empties the overflow from the boiler, receives its supply from a source of fresh water, while the overflow from the boiler passes to a waste 50 pipe. The present invention also contemplates the operation of the water-supply and water-discharge means at a rate of speed which will allow considerable excess to overflow, whereby the water in the boiler will

never become sufficiently concentrated to 55 form scale, or will, even in the case of water of such quality that the formation of some scale is unavoidable, reduce the same to a minimum. By this arrangement the water in the boiler may be maintained almost as 60 pure as fresh water, while the heat inter- changer prevents the disadvantageous and uneconomical loss of heat which would otherwise occur.

A preferred embodiment of the invention 65 is shown in the accompanying drawing, the single figure of which is a diagrammatic view of the steam boiler, feed pump, heat interchanger, measuring engine and other co- operating mechanism. Only those parts and 70 details are shown which are essential to a full disclosure of the invention.

a represents the steam boiler; *b* the desired water level therein; *c* a pipe leading from any source of fresh water; and *d* the feed 75 pump, which takes water from the pipe *c* and delivers it through the heat interchanger *e* into the boiler.

A measuring engine (hereinafter de- 80 scribed) is operated synchronously with the feed pump *d* by any suitable means. I have shown the plungers of the engine and pump connected by a walking beam *f* pivoted be- 85 tween its ends to the frame of a steam engine. The reciprocating piston *x* of the steam cylinder is shown connected to the plunger of the feed pump *d*, while the plunger *h* in the cylinder *g* of the measuring engine is connected to the fly wheel *y* of the steam engine by means of a connecting rod *z*.

The cylinder *g* of the measuring engine has at least as great a capacity as, and pref- 90 erably a greater capacity than, the cylinder of feed pump *d*. It has ports and a slide valve *i* which is operated by a rigid arm *j* on the end of the plunger itself. This arm *j* engages, just before the end of the inward stroke, with a shoulder *k* on the valve stem and shifts the valve *i* to open communication 100 between a pipe *m* (which leads from within the boiler at a point at which it is desired to maintain the water level) and the cylinder *g* of the measuring engine. Just before the end of the outward stroke of the plunger *h* of the measuring engine, the rigid arm *j* en- 105 gages a head *l* on the end of the valve stem and shifts the valve *i* to close communication between the pipe *m* and the cylinder *g* of the

measuring engine, at the same time opening communication between the cylinder *g* and the pipe *n* which leads to the heat interchanger.

5 As long as the water level in the boiler *a* is above the end of the pipe *m*, the cylinder *g*, being of greater capacity than the cylinder of the feed pump *d*, will take more water out of the boiler than the feed pump can deliver into it. When, however, the level of the water in the boiler falls below the end of the pipe *m*, the latter will receive only steam, and the water level in the boiler will rise until equilibrium is established.

15 The heat interchanger *e* is not a substitute for the usual feed water heater operating by exhaust steam from the engine. Should an ordinary heater be used it must be introduced in the pipe *o* between the feed pump 20 and the heat interchanger. The purpose of the interchanger is to neutralize what would otherwise be a waste of heat resulting from a continuous withdrawal of hot water from the boiler.

25 The heat interchanger can be of any of the well known forms, but that shown consists in a coil *p* for the feed water extending through a chamber in which is a series of diaphragms *r*, each perforated with a 30 small hole, thus dividing the interchanger into a series of superimposed chambers, the upper one of which contains the hottest water and transfers heat in the greatest degree to the coil through which the feed 35 water passes. The other chambers grade downward in temperature as the incoming feed water takes heat away from them.

By means of this interchanger the heat units in the stream of withdrawn water are 40 immediately transferred to the ingoing feed water and substantially no heat is lost.

If there were nothing to prevent, the water, as soon as delivered through the pipe *n* into the chambers of the interchanger *e*, 45 would, owing to its high temperature, flash into steam and escape through the drain or waste pipe *q*. Under these conditions, very little of the heat would be saved by the interchanger.

50 To obviate this I provide a differential valve *s* working in a valve casing interposed between the interchanger *e* and the drain pipe *q*. The lower chamber *u* of the valve casing connects with the lower chamber of 55 the interchanger *e* and has a seat for the head of the valve *s* which, when seated, closes the lower chamber *u* from a middle chamber *t* connecting with the drain. The stem of valve *s* slides in a reduced upper 60 end of the valve casing, the space above the stem forming the upper valve chamber *v*, which is connected by a pipe *w* with the steam space of the boiler *a*. The live steam pressure acting through the pipe *w* tends 65 to hold valve *s* down on its seat, thereby

closing the outlet from the heat interchanger. However, the lower end of the valve is larger in area than the end acted on by the live steam; and when the pressure in the interchanger rises sufficiently, it raises 70 the valve, and water from the interchanger escapes through chambers *u* and *t* into the drain pipe *q*. Thus, valve *s* acts as a regulating check valve, allowing exit of the water from the interchanger at a pressure 75 which will vary with the boiler pressure, but will be lower in proportion as the area of the seat is larger than the area of the plunger of the valve.

From the foregoing description it will be 80 understood that water will be supplied by the feed pump at a rate in excess of that required to replenish water in the boiler that is converted into steam and that this excess of water will be continuously withdrawn 85 from the boiler into the interchanger, wherein the heat of the discharged water will be abstracted by the water flowing from the feed pump to the boiler; the temperature of the water discharging into the drain being thereby reduced almost to the temperature of the water flowing into the interchanger from the feed pump. 90

Three important advantages are thereby secured. The feed water is delivered to the 95 boiler in a highly heated condition; the level of the water in the boiler is maintained; and the water in the boiler is constantly being replenished with fresh water, whereby the formation of scale is minimized or altogether avoided. 100

Having now fully described my invention, what I claim and desire to protect by Letters Patent is:

1. In a feed water supply system for 105 steam generators, a water feed line including a pump for continuously supplying a pre-determined amount of fresh water to the generator, an overflow line including a measuring engine for continuously removing 110 the excess water supplied to the generator, a double surface heat interchanger connected to said line, the ingoing water passing over one surface while the outgoing water passes over the other surface, to transfer the heat from the outgoing water to the ingoing water, and means for controlling the discharge of water from the heat interchanger. 115

2. In a feed water supply system for 120 steam generators, a water feed line including a pump for continuously supplying a pre-determined amount of fresh water to the generator, an overflow line including a measuring engine for continuously removing 125 the excess water supplied to the generator, a double surface heat interchanger connected to said lines, the ingoing water passing over one surface while the outgoing water passes over the other surface, to transfer 130

fer the heat from the outgoing water to the ingoing water, and means for controlling the flow of outgoing water from the heat interchanger.

5 3. In an apparatus of the character described, the combination with the boiler, of two pipes leading thereto and otherwise non-communicating, a source of fresh water supply connected with one pipe, the second 10 pipe being connected with the boiler at

the desired water level, a feed pump and a measuring engine connected with the respective pipes, and means connecting the engine and pump adapted to transmit the power delivered by the measuring engine 15 to assist in driving the pump.

In testimony of which invention, I have hereunto set my hand, at Philadelphia, Penna., on this 25th day of May, 1918.

FRANCIS I. DU PONT.
